WAR GAME

Oscar R. Gable, Animas, N. Mex.

Application May 5, 1936, Serial No. 78,029

2 Claims. (Cl. 273—126)

The present invention relates to new and useful improvements in games and has for its primary object to provide, in a manner as hereinafter set forth, a game which will be highly entertaining and in the successful playing of which considerable skill will be required.

Other objects of the invention are to provide a game of the aforementioned character which will be simple in construction, strong, durable, attractive in appearance and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a game board or table embodying the present invention.

Figure 2 is a view in vertical longitudinal section through the invention.

Figure 3 is an end elevational view of the game board or table.

Figure 4 is a detail view in perspective of a cue which is to be used in playing the game.

Figure 5 is a detail view in perspective of one of the surface projectiles or pieces.

Referring now to the drawings in detail, it will be seen that the embodiment of the invention which has been illustrated comprises a flat, horizontal panel or board 1 of any suitable material which is mounted on supporting legs 2. Rising from the edges of the board 1 are side walls 3 and end walls 4 and 5. Extending diagonally between the side walls 3 and the end wall 5 are partitions 6 providing substantially triangular compartments 7 for the reception of two sets of distinctively colored surface projectiles 8 in the form of disks 8. At an intermediate point, the end wall 5 has formed therein a cut-out or recess 9, the purpose of which will be presently set forth.

Defined longitudinally on the board 1, as at 10, is a substantially ovate area or field 11 which is unobstructed and which is known as "No Man's Land". The field 11 is divided into two sections by a transverse line 12. Projecting transversely over the board 1 from the side walls 3 are spaced partitions 13 which terminate, at their inner ends, in heads 14 at the margins 10 of the field 11. The areas between the longitudinally spaced partitions 13 and between the end wall 4 and the adjacent partitions 13 are to be known as forts 15 for the reception of the surface projectiles

or pieces 8. Mounted on the end wall 4 is a tray 16 which is adapted to receive the pieces 8 from the board 1 through an opening 17 in said end wall 4. Guides 18 are provided on opposite sides of the opening 17 for deflecting or directing the pieces 8 toward said opening.

The ports 15 are alternately colored, for example, red and black and the two sets of disks 8 are similarly colored. The forts 15 are further provided with score indicating numerals 19 and 10 and also with suitable indicia 20 which is suggestive of the scoring value of the different forts. The two halves into which field 11 is divided by the transverse line 12 are also provided with score indicating numerals 21 and suitable indicia 22 15 indicating the nature of this area and suggesting the scoring values thereof. At one end of the field 11 and at an intermediate point on the line 12 marks 23 and 24 are provided, said marks being representations of stars. The reference 20 numeral 25 designates a conventional cue with which the pieces 8 are propelled.

Briefly, the game may be played substantially as follows:

The sets of pieces 8 may be stored in their respective compartments 7, said compartments being known as arsenals, as indicated at 26. The compartments 7 are colored to conform to the colors of the two sets of pieces 8. Two, four or more players may compete in the game. Before starting the game the players place a piece 8 on the spot 23 and shoot said piece through the medium of the cue 25, as close as possible to the spot 24. The player coming the closest to the spot 24 in this preliminary contest has his choice 25 of the two sets of pieces 8 and also the order in which he is to play. Ten of the pieces 8 may comprise each set. The playing of the game now starts, the player placing his pieces on the board 1 adjacent the head of the table or game and projecting said pieces over the field 11 through the medium of the cue 25. The recess 9 in the end wall 5 is to accommodate the cue 25 when propelling the pieces 8. The object of the game is to cause the pieces 8 to enter the forts 15 of 45 the player, as indicated by the color of said forts. In other words, the player using the red pieces 8 endeavors to shoot the same into the red forts 15, etc. This must be done by banking the pieces 8 from the inner end portions of the partitions 13 50 on the opposite side of the board 1. Should one of the pieces 8 be shot into a fort of the opposing player, that piece becomes a captive and the score of that particular fort counts double for the opponent. The pieces 8 which come to rest in either 55

section of the field 11 may be driven into the forts 15 by subsequently shot pieces. This may be done either by the player to whom the pieces belong or by the opponent who follows him. Any 5 of the pieces 8 remaining in the field 11 at the end of play count according to the scoring value of that section, as indicated at 21. Any of the pieces 8 which pass through the opening 17 into the tray 16 are "dead" or out of play for the 10 rest of the game. After all of the pieces have been played the scores are added to determine the winner of the game. Should either player succeed in placing one or more of his disks 8 in each of his forts 15 he is the winner and the 15 game is thus terminated.

It is believed that the many advantages of a game constructed in accordance with the present invention will be readily understood, and although a preferred embodiment of the device is as illustrated and described, it is to be understood that changes in the details of construction and in the combination and arrangement of parts may be resorted to which will fall within the scope of the invention as claimed.

Having thus described the invention, what is claimed as new is:

1. A game device of the class described com-

prising a horizontal board, side and end walls rising from said board, spaced partitions extending inwardly from the opposite side walls and including heads on their inner ends engageable by game pieces, said partitions defining scoring chambers for the reception of the game pieces.

2. A game of the character described comprising a horizontal board having defined longitudinally thereon a substantially ovate field spaced from the sides of said board, side walls rising from the board, spaced partitions extending inwardly from the opposite side walls and terminating at the edge of said ovate field, said partitions defining scoring chambers for the reception of game pieces from the field, said partitions terminating in heads at their inner ends engageable with the game pieces for deflecting said game pieces, one of the walls adjacent one end of the ovate field having a cut-out portion for the manipulation of a game piece projecting implement 2 along the surface of the board and a pair of deflectors secured to the board adjacent the opposite end of the ovate field, said deflectors having inclined faces cooperating to form an end chamber.

OSCAR R. GABLE.
